RUDOLF BLANCKERTZ, OF BERLIN, GERMANY, ASSIGNOR TO THE FIRM: HEINTZE & BLANCKERTZ, OF BERLIN, GERMANY

PEN FOR DRAWING AND RULING PURPOSES

Application filed October 2, 1926, Serial No. 139,152, and in Germany October 5, 1925.

This invention relates to a pen for drawing and ruling purposes which in a preferred embodiment is to a certain degree similar, as regards its construction, to an ordinary writing pen, which can be conveniently handled, which is extremely cheap to manufacture and which allows the drawing of lines of even thickness irrespective of the pressure manually exerted thereon.

10 The writing pens as now in use for drawing purposes have split or slit points and the two elastic shanks forming the split point of the pen are spread under the influence of the pressure exerted thereon. 15 Such pens, owing to the uncontrolled pressure exerted thereon in operation produce lines of irregular thickness. This is objectionable for several kinds of work and therefore draftsmen are accustomed to use 20 special drawing pens to obtain lines of even thickness as long as they are used without change of adjustment. If, however, in a special kind of work it is necessary to produce lines of different thickness, each thickness indicating a special meaning or value, then the use of the known drawing pens is 25 troublesome owing to the difficulty of securing the appropriate adjustment for each thickness of lines. It would also be a cumbersome and expensive method to use a 30 plurality of drawing pens for such work, each pen being used only for drawing lines of a definite thickness.

The pen according to this invention although as above stated similar in construction and handling to a normal writing pen is distinguished from the usual writing pens in that its point is shaped to form a small disc or plate which is bent at an angle to the 35 axis or body of the pen, an ink feeding longitudinal slot being provided in the pointed end of the pen to extend across the bend and in the said disc or plate without, however, interrupting the continuity of the 40 extremity thereof, so that the width of the disc or plate will always be the same and consequently also the width or thickness of the drawn lines will always be accurately 45 the same irrespective of the pressure manually imparted to the drawing instrument,

while at the same time the ink feeding slot will ensure the necessary contact between the ink and the drawing paper or the like or in other words the lower surface of the said small disc or plate which is to be held in contact with the paper or the like during the drawing operation, will be properly supplied with ink stored up in the slot and in the vicinity thereof and this will be accomplished by the provision of a slot extending 55 down across the bend and partly into the face of the said small disc or plate.

The small disc or plate forming the active point of the pen may be given a circular, elliptic, or any other suitable shape and 60 may be integral with a pen which in its general aspect is similar to an ordinary writing pen or integral with a shoe adapted to be frictionally attached to an ordinary writing pen or any other sort of an appropriate holder. In the case where the invention is in the form of an attachment for an ordinary writing pen, the latter forms an 65 ink-holder and its elastic slotted point, due to its opening when it is forced against the 70 disk-like end, or shoe, of the attachment, has a regulating effect upon the quantity of ink 75 transmitted to the disk contacting with the paper and producing the lines thereon.

With the above recited and other objects 80 in view, reference is had to the following specifications and drawings in which there are exhibited a few examples or embodiments of the invention which are in no way intended as a limitation upon the scope of 85 the appended claims as it is to be clearly understood that variations and modifications which fairly fall within the true scope of the appended claims may be resorted to when found expedient.

In the accompanying drawings forming a 90 part of this specification and wherein like characters designate like parts throughout the several views:

Figure 1 is a plan view of a sheet steel blank 95 from which a drawing pen similar in shape to an ordinary writing pen, is to be made by a bending operation and Figure 2 is a perspective view of the finished pen made from the blank shown in Figure 1; Figures 3 to 5 100

illustrate a modified construction of the drawing pen, Figure 3 being a plan view of the blank, Figure 4 being a longitudinal sectional view of the finished pen and Figure 5 being a front view thereof; Figures 6 to 8 show a further modification; Figure 6 being a plan view of the blank, Figure 7 being a side view of the finished pen and Figure 8 being a front view of the pen; Figures 9 to 11 illustrate an embodiment of the invention in the form of a shoe adapted to be attached to a common writing pen or any other appropriate holder, Figure 9 being a front view of the shoe-shaped drawing pen, Figure 10 being a longitudinal sectional view thereof and Figure 11 being a front view showing the same attached to a common writing pen; Figure 12 shows a modified construction of a shoe-shaped drawing pen attached to a common writing pen and Figure 13 an enlarged cross-section along the line 13—13 of Figure 12.

Referring to Figures 1 and 2 the tapering end of the pen is elongated to form a small circular disc *a* and a longitudinal slot *b* is provided therein. The small disc *a* does not lie in the plane of the pen but is bent off so that the plane of the pen and the plane of the disc intersect and the disc is situated at a predetermined angle with relation to the body of the pen. The tapering end of the pen is slotted in its median line and the slot *b* extends beyond the bend *c* so that the disc *a* will be partially slotted as will be clearly seen in the several views of the drawings, and ink will be fed through the slot to the lower face of the disc which is to be held in flat contact with the paper or cardboard during the drawing operation.

The bent off disc with an ink-feeding slot therein leaving the extremity thereof uninterrupted is the most salient feature of the invention and adapted to ensure a perfectly even ink supply and perfectly even lines of constantly the same width or thickness. The uninterrupted contour of the disc secures smooth sliding of the pen over the surface of the paper and great durability of the pen, moreover it can be more easily and cheaply manufactured than a slotted point. The disc may have any desired form.

In the modification shown in Figures 3 to 5 the pen is provided with a means constituting a kind of a reservoir for ink. To this end the body of the pen is cut to form a flap or tongue *z* and the latter is bent outwards over and along the front or top or ridge of the pen in a curved line and with its free end nearly in contact with the bend *c* as will be readily understood on inspection of Figure 4. The chamber or cavity thus formed between the tongue *z* and the slotted end of the pen co-operates with the slot *b* to store up a larger quantity of ink than can be done by the slot alone.

The modification illustrated in Figures 6 to 8 comprises a broad plate *a* of approximately elliptic shape for drawing very thick lines. In structures of this configuration it is advisable to provide a plurality of longitudinal slots and preferably also a corresponding plurality of storage tongues. In the example shown two slots *b* and two tongues *z* are provided, the free ends of the latter lying nearly in contact with and opposite the bend *c* as above described. The ink reservoir forming tongues *z* is shown as being arranged on the upper, front or top side of the pen; I desire however to have it understood that any other arrangement could be used without departure from the gist of the invention.

According to Figures 11 and 12 the drawing pen proper forms only one element of a compound structure, a further element being formed by a common writing pen which has the function of a carrier for the drawing pen proper and of a regulating device for the ink supply.

According to Figures 9 and 10 the element of the compound structure of Figure 11 which forms the drawing pen proper is provided with a bent off disc like point *a* and with a longitudinal slot *b* crossing the bend *c* without however severing the disc *a* entirely. The plate like body portion of this element is provided with two lateral flanges or wings *d* bent to form sliding guides so as to give it the character of a shoe adapted to be slipped upon a suitable holder, the holder consisting according to Figure 11 of a common writing pen.

In the modification illustrated in Figures 12 and 13 the shoe like element of the compound structure is equipped with two pairs of flanges or wings *d* and *e*, the pair *d* forming sliding guides adapted to be slipped over the edges of a suitable holder, such as a writing pen or the like, the pair *e* forming a kind of envelope for the tapering end of the carrying writing pen as clearly shown in Figure 13 adapted to receive a supply of ink.

In operation the disc *a* of the shoe element of the compound structures of Figures 11 and 12 presses on the slotted point of the carrying writing pen so as to spread the resilient shanks of the pen more or less and regulating thereby to some extent the transmission of ink to the plate *a*. The construction allows the combination of shoe members having differently shaped discs with writing pens having points of any desired shape or elasticity of their shanks.

What I claim is:—

1. A pen for drawing and ruling purposes provided with a writing point ending in a bent disc and provided with a longitudinal slot, said longitudinal slot extending into said disc and terminating short of

the rim thereof, the rim of said disc being unbroken.

5 2. A pen structure for drawing and ruling purposes comprising two elements, the one consisting of a normal writing pen having a tapering slotted end, the other forming a shoe member having flanges cooperating with the lateral edges of said writing pen to attach the said member thereto, said shoe member terminating in an angularly disposed disc for surface contact with the paper, and a longitudinal slot in said disc and terminating short of the rim thereof, said rim being unbroken.

10 15 3. The structure as in claim 2 wherein the end of the writing pen normally rests on the upper surface of said disc, whereby pressure on said disc spreads the shanks of said writing pen.

20 4. The structure as in claim 2 wherein said shoe member has a pair of bent-in edges adjacent said disc for receiving a supply of ink.

25 5. A pen for drawing and ruling purposes, comprising a body having a tapering end, a small plate integral therewith to form the extremity thereof and which is bent out of the plane of said tapering end, a longitudinal slot in the body and extending into 30 said plate and terminating short of the rim thereof, the rim of the plate being unbroken, and lateral wings bent over to form sliding guides for attachment to a suitably shaped holder.

35 6. A pen structure for drawing and ruling purposes comprising two elements having tapering ends arranged in superposition to each other, the one element forming the drawing pen proper being provided with a 40 small plate forming the extremity of the tapering end, said plate being bent out of the plane of the tapering end, a longitudinal slot in the plate and crossing the bend between said plate and the adjacent portion 45 of the element and terminating short of the rim of said plate, said plate having an unbroken rim, the compound structure consisting of a normal writing pen, the point thereof substantially coinciding with the 50 bend in the first named element.

In witness whereof I affix my signature.
RUDOLF BLANCKERTZ.
